INTERNAL COMBUSTION ENGINE VALVE

John H. Grube, Pasadena, Calif.

Application June 8, 1942, Serial No. 446,283

5 Claims. (Cl. 123—81)

This invention relates to improvements in internal combustion engines and more particularly pertains to valve mechanism for such engines.

The primary object of this invention is to provide valve mechanisms which will increase the general efficiency of an internal combustion engine by affording the advantages and improvements as follows:

1. Increased volumetric efficiency.
2. Higher power peak.
3. Quicker acceleration.
4. Minimized friction, vibration and noise.
5. Higher compression ratio.
6. Automatic wear compensating adjustment of the valves.
7. Uniform expansion and elimination of sticking of the valves.
8. More efficient cooling of the valves.
9. Accessibility and replacement of valve parts and removal of carbon without requiring removal of engine head.
10. Low power operation of valves.
11. Maintained timing adjustment, once set.

Another object of my invention is to provide an improved valve mechanism of the character described wherein individual intake and exhaust valves per cylinder, and in the form of frusto-conical plugs operated with an oscillatory movement, achieve the improvements and advantages defined herein in a particularly efficacious manner.

A further object of my invention is to provide a novel drive or operation means for the valves of my invention which is simple, inexpensive and reliable in performance over long periods of use without requiring adjustment or replacement of parts and also prevents the valves from sticking while permitting of automatic wear compensating adjustment of the valves.

Yet another object of my invention is to provide an internal combustion engine valve such as described which has a lubricated and fluid cooled seat and thereby "floats" on the lubricant and operates with greater precision, nicety of control and efficiency than possible with the present-day types of rotary, slide or poppet valves.

With the foregoing objects in view, together with such other objects and advantages as may subsequently appear, the invention resides in the parts and in the combination, construction and arrangement of parts hereinafter described and claimed, and illustrated by way of example in the accompanying drawing, in which:

Fig. 1 is a fragmentary vertical sectional view, partly in elevation, of an internal combustion

engine valve mechanism embodying my invention;

Fig. 2 is a fragmentary horizontal sectional view taken on the line 2—2 of Fig. 1 showing the valve closed;

Fig. 3 is a fragmentary horizontal sectional view taken on the line 2—2 of Fig. 1 showing the valve open;

Fig. 4 is a fragmentary horizontal sectional view taken on the line 4—4 of Fig. 1 to illustrate the spring means for closing the valve;

Fig. 5 is a fragmentary horizontal sectional view taken on the line 5—5 of Fig. 1, to illustrate the cam means;

Fig. 6 is an enlarged fragmentary part section—part elevational view showing the formation of the valve and the manner of connecting it with the drive shaft therefor.

In accordance with my invention separate intake and exhaust valves are provided for each cylinder of an internal combustion engine with each valve constructed and arranged as shown in Fig. 1 of the accompanying drawing wherein A designates one of my improved valves, B the cylinder head, C an engine cylinder, and D the valve operating means.

As here provided the valve A is of the plug type, that is, it is in the form of a truncated cone and preferably hollow. In opposite sides of this valve are elongated ports 7 and 8 respectively adapted to be brought into and out of registration with ports 9 and 10 in opposite sides of a frusto-conical valve seat 11 formed in the cylinder head duct 12 which latter opens into the combustion chamber C₁ of the cylinder C. The valve seat 11 extends through the lower wall 13 of the head B part way as a conical portion 11a and the remainder as a cylindrical portion 11b. Similarly the "seat" extends through the upper wall 15 of the head in the form of a conical inner portion 11c and a screw threaded and somewhat enlarged cylindrical outer portion 11d. The remainder of the seat 11 is formed by the transversely curved vertical sections 11e and 11f of the walls of the duct 12 as shown in Figs. 2 and 3, which sections are contiguous with the seat portions 11a and 11c.

It will be observed that the valve seats on the aforesaid conical portions of the seat 11 in such manner that it will automatically accommodate itself to seat in case of wear and is subject to a slight lifting and consequent "loosening" during its operation as a result of the operating thrust imparted thereto as will be hereinafter more fully described, and moreover when

the force of the expanding gases (exhaust) is applied thereto thereby preventing "sticking" of the valve.

On the upper end of the valve is a thrust washer 16 which has an axially slidable fit in a cylindrical counter bore 11g as shown in Fig. 6, so that a spring loaded thrust pin 17 in a plug 18 may be effective against said washer to urge the valve into properly seated position, said plug being screwed into the threaded portion 11d. The plug 18 is spaced from the washer whereby the latter may be moved freely outward as well as inward with axial movement of the valve.

The lower end of the valve seated in the seat portion 11a is provided with an elongated slot 19 of rectilinear outline, adapted to receive a drive key 20 provided on the upper end of a sectional drive shaft 21, as shown in Fig. 6. The slot 19 is longer than the drive key so that the upper end of said key is spaced from the inner end of said slot and the valve is therefore free to move axially while at the same time being drivingly connected with the drive shaft by means of the parallel opposed flat sides of the slot and drive key which are in sliding contact with one another at all times.

The head B is provided with a water jacket 22 surrounding the valve seat and valve area of the head as will be seen in Fig. 1 to insure effective cooling of the valve.

Means is provided for maintaining a coating of film of lubricant on the valve and its seat to improve the efficiency of the valve and engine as a whole. As here shown the valve is provided adjacent its upper and lower ends with circumferential oil grooves 23 and 24 joined by longitudinal grooves 25 at spaced intervals around the valve. An oil pressure feed port 26 in the head B opens into the groove 24 to supply under oil pressure from a source not shown to the oil grooves in the valve.

I have found that a valve constructed as hereinbefore described and as shown in the accompanying drawing, when opened and closed with an oscillatory movement affords the improvements hereinbefore noted in a highly efficacious manner and consequently the operating means D is designed to oscillate the valve in the particular manner here disclosed.

As here provided the upper section 21a of the drive shaft 21 is drivingly and relatively axially adjustably coupled to an intermediate section 21b of the shaft by means of wedge drive key 27 fixed to the upper section 21a and fitted in a similarly shaped notch 28 at the upper end of the intermediate section. A sleeve 27a is fitted over the joint. This joint functions to provide somewhat of a cam action for lifting the upper section of the shaft and the valve incident to an operating impulse transmitted to the valve whereby the valve will be prevented from sticking and will operate more efficiently. By the use of said sleeve 27a to keep the two shaft sections aligned the shaft is made to function in the manner stated without any objectionable increase in the diameter of the joint portion thereof.

At its lower end the section 21b of the drive shaft is provided with a drive key 29 of rectilinear form which engages in a "square" notch or socket 30 in the upper end of the short lower section 21c of the drive shaft, in the same manner as the valve is coupled to the upper end of the drive shaft. This lowermost shaft section 21c is supported in a portion 31 of the engine block, there being a thrust bearing 32 at the upper end

of the shaft section and nuts 33 which latter hold the shaft in place.

The lower end of the shaft section 21c is provided with a crank arm 34 from which a crank pin 35 depends. A thrust plate 36 is carried by said pin so that it is engaged by a cam 37 on the engine driven cam shaft 38, whereupon the drive shaft as a whole is rotated through a part of one revolution for opening the valve, with each revolution of the cam shaft.

As a means for turning the drive shaft in the opposite direction to close the valve following a cam effected impulse of the drive shaft, a coiled leaf spring 40 is employed. This spring is adapted to be contained in the narrow space between the shaft and engine cylinder and has one end fixed in a slot 41 in the shaft section 21b and its other secured by means of screws 42 to the cylinder of the engine as shown in Figs. 1 and 4.

Spring means is provided for urging the shaft 21 downwardly and properly holding together the joints formed between the shaft sections 21a, 21b and 21c. This means includes a spring keeper ring 43 mounted on the shaft section 21a and abutting the cylinder head as shown in Fig. 1, with the upper end of a helical spring 43' in contact therewith while the lower end of the spring engages a collar 44 which rotates a thrust bearing 44' carried on said shaft section.

It is now apparent that when the cam means turns the shaft 21 for opening the valve 11, it being noted in Figs. 2 and 3 that but a small amount of movement of shaft is required, the turning force transmitted to the drive wedge 27 from the shaft section 21b produces a cam action and causes the shaft section 21a to be lifted, whereby the valve will be somewhat lifted and thereby prevented from sticking or freezing. This insures a smooth valve operation under a comparatively low operating force.

Inasmuch as the valve is axially adjustable on a cooled and lubricated seat and is also lubricated and preferably made of a metal having a low coefficient of expansion, and in view of the use of the sectional drive shaft in which the sections are axially movable relative to one another and the valve, it is seen that the valve will be prevented from sticking and will automatically adjust itself to compensate for wear, also operate in a much more reliable and efficient manner due to the "flexibility" of the valve mechanism as a whole and the small amount of friction present in the operation thereof.

The cam means, the drive shaft and the valve are so constructed that the ports will be fully opened and closed more quickly than possible with rotary, slide and poppet valves, and remain open for a longer period, thereby increasing the efficiency of the intaking and exhausting action, or in other words, the volumetric efficiency of the engine.

It should be noted that in comparison with a conventional poppet type exhaust valve having a dead lift of say sixty pounds, my valve "floats" this load with twelve pound thrust of the cam follower. This differential of forty-eight pounds per thrust on an eight cylinder engine turning up 32,000 R. P. M. amounts to many tons of energy released for engine torque. It is now apparent wherein my improved valve is much more efficient than poppet valves and affords the advantages hereinbefore noted in a particularly efficacious manner.

It should be noted that the thrust pin and spring in the valve retaining nut provide for au-

tomatic compensation for wear and automatic adjustment to take care of expansion and contraction of the valve and its housing, also effectively oppose the explosion pressure imposed on the closed port area of the valve which, due to the beveled shape of the valve, would otherwise lift the valve off its seat at the most critical instant of its compression holding period.

Also it is to be noted that, owing to the slight clearance normally present above the key 20 (Fig. 6), the upper shaft section 21a gains a slight impetus when forced upward by the joint structure between the two sections of the shaft 21, so as more efficiently to loosen a "stuck" valve.

While I have shown and described a specific embodiment of my invention I do not limit myself to the exact details of construction set forth, and the invention embraces such changes, modifications and equivalents of the parts and their formation and arrangement as come within the purview of the appended claims.

I claim:

1. In an internal combustion engine valve structure, a cylinder head having a duct for communication with a cylinder and provided with an opening through an outer surface thereof, a conical valve seat extending through said duct from said opening and having elongated ports opening into said duct, a conical valve adapted to be inserted through said opening to engage said seat and having a port extending transversely therethrough for registration with the ports in said seat, plug means closing said opening and retaining said valve on its seat, including spring means yieldingly urging said valve against its seat, a sectional shaft connected with said valve and in a parallel adjacent relation to the engine cylinder, a joint between sections of the shaft arranged to provide a cam action and slightly lift the valve from its seat incident to an operating impulse being imparted to the shaft, and means for oscillating said shaft including a coiled spring having one of its end portions connected to said shaft and its opposite end portion connected to the adjacent part of said engine cylinder.

2. In an internal combustion engine valve structure, a cylinder head having a duct for communication with a cylinder and provided with an opening through an outer surface thereof, a conical valve seat extending through said duct from said opening and having elongated ports opening into said duct, a conical valve adapted to be inserted through said opening to engage said seat and having a port extending transversely therethrough for registration with the ports in said seat, plug means closing said opening and retaining said valve on its seat, including spring means yieldingly urging said valve against its seat, a sectional shaft for operating said valve, a joint between the smaller end of the valve and a section of the shaft, affording a slight relative movement of the valve and said shaft while maintaining a driving connection between the valve and the shaft, a second joint between sections of the shaft arranged to provide a cam action and slightly lift the upper section of the

shaft till it acts upon and lifts the valve from its seat incident to the shaft being given an operating impulse, and mechanical, engine operable means to oscillate said shaft.

3. In an internal combustion engine valve structure, a cylinder head having a duct for communication with a cylinder and provided with an opening through an outer surface thereof, a conical valve seat extending through said duct from said opening and having elongated ports opening into said duct, a conical valve adapted to be inserted through said opening to engage said seat and having a port extending transversely therethrough for registration with the ports in said seat, plug means closing said opening and retaining said valve on its seat, including spring means yieldingly urging said valve against its seat, a sectional shaft for operating said valve, a joint between the smaller end of the valve and a section of the shaft, affording a slight relative movement of the valve and said shaft while maintaining a driving connection between the valve and the shaft, a second joint between sections of the shaft arranged to provide a cam action and slightly lift the valve from its seat incident to the shaft being given an operating impulse, cam means for oscillating said shaft including a crank arm on a section of the shaft, a crank pin depending from said arm, a thrust plate fixed on said pin, and a cam working against said thrust plate.

4. In an internal combustion engine valve structure, a cylinder head having a duct therein positioned to communicate with an engine cylinder, a frusto-conical valve seat intersecting said duct and having ports opening into said duct, a frusto-conical valve occupying said seat, a drive shaft axially related to said valve and connected to the smaller end thereof, said shaft being in two sections, one of said sections having a wedge-shaped end and the other section having a notch into which said wedge-shaped end extends to form a joint, a sleeve carried by and fitted around said shaft in a surrounding relation to said joint, means to oscillate said shaft about its axis to operate said valve, the two sections of said shaft withdrawing from each other sufficiently to loosen the valve from its seat whenever fixation of the valve to its seat occurs, and a spring operatively connected with said valve yieldingly to hold it to its seat.

5. In an internal combustion engine, an engine cylinder having a head furnished with a duct which leads into an adjacent end of said cylinder, a valve seat intersecting said duct, a valve mounted in said seat to control the flow of fluid through said duct, an operating shaft for said valve, said shaft extending substantially parallel to the wall of said cylinder in an exterior adjacent relation thereto, a coiled leaf spring having one of its end portions attached exteriorly to the wall of said cylinder and its opposite end portion attached to said shaft, said spring being arranged yieldingly to hold said valve in a normally closed position, and engine operable means to turn said shaft to open position against the opposition of said spring.

JOHN H. GRUBE.
